UNITED STATES PATENT OFFICE

ERNEST GREEN, OF LONDON, ENGLAND, ASSIGNOR TO RADIO CORPORATION OF AMERICA, A CORPORATION OF DELAWARE

RADIO FREQUENCY CIRCUIT ARRANGEMENT

Application filed February 15, 1929, Serial No. 340,049, and in Great Britain March 7, 1928.

This invention relates to circuit arrangements for use with high frequency currents, and is particularly applicable to amplifying systems dealing with very high radio frequencies. More particularly the invention relates to amplifying systems of the kind in which a Wheatstone bridge arrangement is employed to decouple the input and output circuits associated with a thermionic valve 10 amplifier, in order to prevent reaction at high frequencies. Bridge arrangements of the kind are described in the specification of the prior United States application Number 43,924, filed July 16, 1925.

15 The present invention has for its objects to provide an amplifier of the kind referred to, which shall serve as a frequency changer, which shall remain balanced over a range of frequencies, and in which an improved efficiency shall be obtained without undesired reaction between the output and input circuits.

According to this invention a Wheatstone bridge amplifying system in which the output circuit is tuned to a harmonic of the input circuit comprises bridge arms whose 25 capacitative reactance, inductive reactance and resistance are equal each to each, while predominantly inductive reactance at output 30 frequency is provided in the lead or leads to the grid or grids of the valve or valves in the said bridge, the arrangement being such that alternating potential of output frequency is applied to the said grid or grids 35 and since the said bridge remains balanced, no current of output frequency is fed back to the input circuit.

In one way of carrying out the invention, the grid-anode space of an amplifying thermionic valve is placed in one arm of a Wheatstone bridge, the other three arms of which comprise each a variable condenser, a variable resistance and a variable inductance in series. The arm containing the grid-anode space of the valve also contains a variable resistance, a variable inductance and a variable condenser, in series with one another, and with the said grid-anode space. Chokes or equivalent devices are provided to 45 permit the flow of direct current to the grid

of the valve. The output circuit (which is tuned to a harmonic of the input circuit) is connected between that corner of the bridge to which the anode is connected and the opposite corner, and the input circuit is connected to form the other diagonal of the bridge, both circuits being arranged symmetrically as respects earth potential. A high resistance may be connected across the input circuit, and its centre point earthed to prevent any tendency of the system to oscillate to earth as a whole. Alternatively, a neutral point in the input circuit may be earthed through a resistance for a like purpose.

The elements in the arm of the bridge (hereinafter called the grid-arm) containing the grid of the valve, are adjusted so as to provide an inductive reactance at the output frequency between the said grid and the corresponding diagonal point of the bridge. The required inductive reactance may, in some cases, be obtained by virtue of the connection leads themselves; in others it will be necessary to adjust the variable inductance in the grid arm to obtain the desired value. Where the connection leads do not themselves provide sufficient inductance and the use of the said variable inductance is necessary, the condenser in the grid-arm may be omitted; at very high frequencies, however, it will generally be found that the said connection leads provide more than sufficient inductance, in which case the variable condenser is adjusted to compensate for excess inductance. The required inductance having been obtained in the grid-arm, the remaining arms of the bridge are then adjusted so that the effective capacitative reactance, inductive reactance and resistance in all four arms 80 are equal each to each. In this manner balance is maintained over a range of frequencies, while, owing to the effective inductance in the grid circuit of the valve and the effect of the output current flowing across the bridge, certain voltage of the output frequency in correct phase is applied to the grid, without loss of balance and without undesired reaction.

It will, of course, be appreciated that large

grid bias and a strong "drive" should be provided, in order to ensure that the output circuit shall be energized at the harmonic frequency.

5 The above described circuit may be employed for all harmonics. If odd harmonics only are required, the circuit should be modified (in a manner known per se) to include a thermionic valve in each of two opposite 10 arms of the bridge.

15 Obviously, if desired, the required conditions of balance may be obtained by suitably dimensioning and arranging the leads and components employed in the bridge, so as themselves to provide the whole or part of the desired resistance and reactance values. Preferably, however, variable impedance devices are provided in the bridge for purposes of adjustment.

20 The invention is illustrated in the accompanying drawing of which Figs. 1 and 2 show in conventional diagrammatic form two modifications in accordance with the said invention.

25 Referring first to Figure 1, this shows an arrangement generally similar to those disclosed in the prior United States application Number 43,924, hereinbefore referred to, and parts corresponding in Figure 1 to parts 30 shown in the said prior disclosure are indicated by like reference letters and numerals.

35 A, G and F are respectively the anode, grid and filament of a valve. The condenser formed by A and G is included in one of the arms of a Wheatstone bridge, the other arms including condensers C1, C2 and C3, and small adjustable resistances r_1 , r_2 , r_3 and r_4 .

40 A small condenser n is connected from the common point 3 of C1 and C2 to earth, the primary circuit being connected across points 1 and 2 and the grid circuit across 3 and 4.

45 The primary circuit comprises inductances L1 and L2 and adjustable condensers K1 and K2, the positive high tension power supply being connected at the point X between the inductances.

50 The grid circuit comprises the inductance V and adjustable condensers R1 and R2, and, as will be seen, the variable condensers of the primary and grid circuits are each constituted by two condensers in series with the centre point earthed; this is desirable, but 55 not essential.

58 Across the grid circuit are two resistances W1 and W2 in series, with their common point connected through a blocking condenser Z to earth, and the inductance V of the grid circuit is coupled to the output circuit of a drive oscillator (not shown). B is a bias battery shunted by a condenser Z1.

It will be noted that as so far described, the arrangement is substantially identical

with that disclosed in Figure 1 of United States application Number 43,924.

In applying the present invention to this arrangement, adjustable inductances P1, P2, P3, P4 are inserted one in each arm of the 70 bridge. D1 is an adjustable condenser inserted in the grid-arm of said bridge, and M is a choke to supply the grid feed. S is a resistance.

75 The input circuit (V, R1, R2 and the associated portion of the bridge) is tuned to the fundamental frequency, while the output circuit (L1, L2, K1, K2 and associated portion of the bridge) is tuned to the harmonic frequency. The variable resistances, inductances and capacities in the bridge arms are 80 adjusted to make the resistance, inductance and capacity in all the said arms equal to each other. In other words, if r'_1 , r'_2 , r'_3 , r'_4 , are the respective total resistances of the 85 bridge arms, P1', P2', P3', P4' the respective total inductances, and C1', C2', C3', the total capacities of three of the arms, that of the grid arm being the capacity D1 in series with the grid-anode capacity of the valve, then the adjustment should be such that $r'_1 = r'_2 = r'_3 = r'_4$; $P1' = P2' = P3' = P4'$; $C1' = C2' = C3' =$ the capacity of the said grid arm. The adjustment is also such that in addition to fulfilling this requirement, the parts P4 and D1 provide an inductive reactance between the points 4 and G at the output frequency.

90 In cases where the frequencies to be dealt with are low, a separate condenser D1 may be dispensed with, it being possible to obtain the desired inductive reactance between the points 4 and G by adjustment of the element P4. Similarly, where very high frequencies 95 are in question, the separate inductances P1, P2, P3, P4 may be dispensed with, the necessary inductive values (which at very high frequencies will be exceedingly small) being obtained by suitably arranging the various connecting leads and the adjustment to obtain the desired inductive reactance between the points 4 and G being obtained by means of the condenser D1.

100 Figure 2 shows a modification, in which two valves are provided and which is suitable for the production of odd harmonics. The electrodes of the second valve are designated by the letters A', G' and F' and, as will be seen, the grid feed choke M, resistance S, and the condenser D1 are duplicated for the two valves and are shown at M1, M2; S1, S2 and D1, D2.

105 As in the previous embodiment, the condensers D1 and D2 may be dispensed with at low frequencies and the inductance coils P1, P2, P3, P4 may be dispensed with at very high frequencies.

Having now particularly described and ascertained the nature of my said invention and in what manner the same is to be

performed, I declare that what I claim is:

1. In an amplifying system, a thermionic valve, a circuit for impressing signal oscillations on the input elements thereof, an output circuit therefor, said first named circuit and said output circuit being uncoupled magnetically, and means for applying the oscillations in said output circuit to the input elements of said valve, including means for preventing exchange of current between said circuits.

2. In an amplifying system, a thermionic valve, a circuit for impressing signal oscillations on the input elements thereof, an output circuit therefor tuned to a harmonic of the frequency of the impressed oscillations and means for applying the oscillations in said output circuit to the input elements of said valve including a balanced bridge circuit adapted to prevent a transfer of current between said circuits.

3. In an amplifying system, a thermionic valve, a circuit for impressing signal oscillations on the input elements thereof, an output circuit tuned to a harmonic of said signal oscillations connected to the output elements of said tube, and means for applying the voltage oscillations in said output circuit to the input elements of said valve, including inductances reactive at harmonic frequency for preventing energy transfer between said circuits.

4. A Wheatstone bridge amplifying system whose output circuit is tuned to a harmonic of the input circuit frequency said system comprising bridge arms whose capacitative reactance, inductive reactance and resistance are equal each to each, while predominantly inductive reactance at output frequency is provided in the lead to the grid of the valve in the said bridge, the arrangement being such that alternating potential of output frequency is applied to the said grid and since the said bridge remains balanced, no current of output frequency is fed back to the input circuit.

5. An arrangement as claimed in claim 4, in which variable inductance coils are provided in the bridge arms.

6. An arrangement as claimed in claim 4 in which a variable condenser is provided in an arm of the bridge including the grid of a valve.

7. An arrangement as claimed in claim 4 in which a choke coil is provided in the grid feed circuit of the valve.

8. In short wave oscillation generators, a pair of thermionic tubes in opposed relation, said tubes each having anode, cathode and grid electrodes, an output circuit connected between the anodes of said tubes, a pair of series capacities connected between the anode of each of said tubes and the grid of the other of said tubes and means for impressing oscillations at signal frequency between the points

of connection between said series capacities.

9. In a radio frequency apparatus, a thermionic relay having anode cathode and grid electrodes, a balanced bridge circuit each arm of which includes a capacity and one arm of which also includes the grid to anode capacity of said relay, means for impressing oscillations at signal frequency across a pair of conjugate nodal points on said bridge, a tank circuit connected across another pair of conjugate nodal points on said bridge and means to tune said last named circuit to a harmonic of the signal frequency.

10. A thermionic oscillation generator including a thermionic tube having anode, cathode and grid electrodes, a Wheatstone bridge circuit having balanced arms, one of which includes the anode to grid capacity of said tube, means for impressing voltage oscillations across the input elements of said tube including an energized winding connected across a pair of conjugate nodal points on said bridge, means for tuning said winding to a signal frequency, an output circuit connected across another pair of conjugate nodal points on said bridge circuit one of said points being adjacent to the anode of said tube, means for tuning the output circuit to a harmonic of the input frequency, means including capacity in one arm of said bridge for impressing voltage oscillations at the harmonic frequency from said output circuit to the input elements of said tube, and means in one of said arms for preventing current characteristic of the output current from reaching said input circuit including an inductance reactive at output frequency in one arm of said bridge.

11. In short wave oscillation generators, a pair of thermionic tubes in opposed relation, said tubes each having anode, cathode and grid electrodes, an output circuit connected between the anodes of said tubes, a pair of series capacities connected between the anode of each of said tubes and the grid of the other of said tubes, means for impressing oscillations at signal frequency between the points of connection between said series capacities, and means to tune said output circuit to a harmonic of the signal frequency.

ERNEST GREEN.
